(57) **CLAIM**

The ornamental design for a keypad for a communication device, as shown and described.

DESCRIPTION

FIG. 1 is an isometric view of an ornamental design of a keypad for a communication device showing our new design; and,

FIG. 2 is a front orthographic view thereof.

The broken lines shown in FIGS. 1-2 are included for the purpose of illustrating environmental elements only and form no part of the claimed design. The rear, left side, right side, top and bottom views are omitted and form no part of the claimed design.

1 Claim, 2 Drawing Sheets

FIG. 1

FIG. 2
